UNITED STATES PATENT OFFICE.

HALVER R. STRAIGHT, OF ADEL, IOWA.

VENTILATED BUILDING-BLOCK.

1,322,646.

Specification of Letters Patent. Patented Nov. 25, 1919.

Application filed August 14, 1916. Serial No. 114,739.

To all whom it may concern:

Be it known that I, HALVER R. STRAIGHT, a citizen of the United States, and resident of Adel, in the county of Dallas and State 5 of Iowa, have invented a certain new and useful Ventilated Building-Block, of which the following is a specification.

My invention relates to and consists in certain new and useful improvements in 10 ventilated building blocks of the class illustrated and described in my Patent No. 1,154,219.

In connection with the manufacture of the kind of tile blocks illustrated and described in my said patent, I have in certain instances had difficulty on account of the fact that when the tile are being dried and burned the outer wall of the tile block would dry first before the partition members, and 15 on that account the shrinkage of material which occurs during the drying would cause cracks to develop in the partition members adjacent to the outer wall, thus weakening the finished product. One of the objects of 20 my invention is to avoid this difficulty by so shaping the partition members that when the outer walls dry and shrink before the partitions, the curved partitions will tend to straighten and thus avoid such strains as 25 30 tend to cause the partitions to crack at points adjacent to the walls.

In making circular walls by means of my improved tile and with the form thereof illustrated in my said patent, I have found 35 some difficulty in thoroughly imposing and embedding all of the binding and reinforcing wires in the cement layers between the rows of building blocks, and when the wires are not thoroughly embedded the exposure 40 thereof to the weather tends to permit the wires to rust and become weakened, thus weakening the structure. Another object of 45 my invention is to provide building blocks of this character so shaped that horizontal layers of mortar will be supported over the spaces between the blocks even if 50 these spaces are relatively wide, thus insuring the complete inclosure of all the reinforcing wires or rods and preventing their deterioration on account of rust.

My invention consists in the construction of the blocks, whereby the objects contemplated are attained, as hereinafter more fully set forth, pointed out in my claim and illus-

trated in the accompanying drawings, in 55 which:

Figure 1 shows a perspective view of my improved building block embodying my invention.

Fig. 2 shows a vertical sectional view of a 60 part of a wall constructed of my improved building blocks.

Fig. 3 shows a vertical sectional view of a part of a wall constructed of my improved building blocks, taken on the line 3—3 of 65 Fig. 4, and

Fig. 4 shows a plan view of a part of a circular wall constructed of my improved building blocks.

Referring to the accompanying drawings, 70 my improved block is seen to comprise a top member 10, a bottom member 11, and two side members 12, forming the outer walls of the block, and two substantially horizontal partitions 13 forming what I have 75 hereinafter termed the partition members. The building block is designed in such a manner that it may be formed of clay on the ordinary tile making machines by the use of suitably formed dies, and also so that the 80 ends thereof may be cut off by an ordinary tile cutter and without the use of hand work.

The top and bottom members are arranged in substantially parallel planes and the ends 85 of the block are cut off at an angle divergent from an angle at right angles to the top and bottom members, so that when the building blocks are laid in a wall the top and bottom members may incline downwardly 90 and toward the outer surface of the wall, and the inner and outer ends of the building blocks may both be vertical, as illustrated in Fig. 3.

In order to avoid the danger of having 95 the partition members crack during the drying or burning process, I have arched or curved the partition members 13 upwardly at their centers, as clearly illustrated in Fig. 1. This obviously does not in any way add 100 to the difficulty of manufacturing these block by means of dies, and the advantage gained by this arching or curving of the partitions upwardly is as follows:

After the building blocks have been 105 formed and the tile clay of which they are formed is still in a somewhat pliable condition, the blocks are dried and burned.

I have found that the outer walls are dried first and that during the drying process the clay will shrink. In cases where the partitions are straight this shrinking of the outer walls sometimes causes cracks to develop in the parts of the partitions adjacent to the outer wall when this drying and burning occur. However, by having the central portions of the partitions 10 arched, I have found that when the outer walls shrink during the drying and burning processes, the arched partitions which are still somewhat plastic or pliable will on account of their weight, straighten out 15 to a slight extent, sufficient, however, to prevent cracking at the ends of the partitions where they join the side walls.

These building blocks are employed largely for use in the construction of circular corn cribs and I have found that by 20 having the partitions arched as shown, the ventilating openings through the wall are of such irregular character that material like ears of corn will not readily pass 25 through said openings and is not as likely to pass through the openings as though the partitions were parallel with the top and bottom wall members, so that this arching of the partition performs the double function 30 of preventing the cracking of the partitions during the drying and burning processes, and also makes a wall better adapted for holding such material as ears of corn.

35 In the erection of a circular wall by the use of my improved blocks, it is customary to first build a suitable base 14, inclined downwardly and outwardly, and then to lay the rows of building blocks on said 40 base. The building is usually made circular, as illustrated in Fig. 4, and the blocks are always made of uniform width from end to end. Hence in a circular building the spaces between the side by side blocks 45 are larger at the outer side of the building than they are at the inner side, as illustrated at *a* in Fig. 4.

Furthermore, in such buildings it is customary to lay up the rows of blocks without 50 mortar between the side by side edges, but between the horizontal rows of blocks a relatively thick layer of mortar or cement is used, and in this mortar or cement the cir-

cular binding or reinforcing wires or rods 55 are embedded. It is important that every part of each wire or rod be thoroughly covered by and embedded in the cement. For this purpose I have provided the top surface 10 of each block with a downwardly and outwardly inclined portion 16. At the side edge thereof and below this downwardly and outwardly inclined portion is a shoulder 17. The same construction is used at the under surface of the bottom 11, although this is not of so 65 much importance.

When the mortar or cement that is to be used is of the proper consistency, I have found that when it is placed in a thick layer on the top surface of a row of these building blocks it will adhere to the inclined portions 16 and be retarded by the shoulders 17, so that it will pile up over the space *a* between the side by side blocks and thus form a continuous layer across a row of 75 blocks, in which the wires may be embedded and fully covered.

In connection with the form of building blocks shown in my said patent, I have found that where the top and bottom members of the tile are substantially flat it is difficult in all instances to have the layer of mortar supported across the space between two side by side blocks, and this mortar frequently drops down between the 80 blocks and leaves the wire exposed. This difficulty, however, has been avoided by the use of the inclined surfaces 16 and the shoulders 17.

I claim as my invention:

A masonry structure comprising a plurality of tile arranged in courses, the upper and lower surfaces of the tile being inclined from one surface of the wall or course downwardly and toward the opposite surface, the ends of said tile being arranged in vertical planes, each of said tile having near its side edges comparatively narrow inclined portions terminating in shoulders for the retaining of mortar, reinforcing between 95 the courses and mortar for said reinforcing whereby the mortar around the reinforcing may be thickest at the joints between the tile.

Des Moines, Iowa, May 19, 1916.

HALVER R. STRAIGHT.
